UNITED STATES PATENT OFFICE

154,674

DESIGN FOR A DISPLAY CASE

Warren Gochenour, Jr., St. Paul, Minn.

Application June 17, 1948, Serial No. 147,025

Term of patent 14 years

(Cl. D80—11)

To all whom it may concern:

Be it known that I, Warren Gochenour, Jr., a citizen of the United States, residing in the city of St. Paul, county of Ramsey, and State of Minnesota, have invented a new, original, and ornamental Design for a Display Case, of which the following is a specification, reference being had to the accompanying drawing, forming a part thereof.

In the drawing:

Fig. 2 is a front elevational view of the same;

Fig. 3 is a side elevational view of the same, and

Fig. 4 is a top plan view thereof.

I claim:

The ornamental design for a display case, as shown.

WARREN GOCHENOUR, JR.
